UNITED STATES PATENT OFFICE.

WILLIAM L. BROWN, OF WICHITA, KANSAS.

ELECTRICALLY-HEATED DISPLAY CABINET.

Application filed April 8, 1921. Serial No. 459,567.

To all whom it may concern:

Be it known that I, WILLIAM L. BROWN, a citizen of the United States, and resident of Wichita, in the county of Sedgwick and State of Kansas, have invented certain new and useful Improvements in Electrically-Heated Display Cabinets, of which the following is a specification.

My invention relates to electrically heated cabinets for holding and displaying peanuts, chestnuts, or other edibles that are intended to be kept and sold in a hot condition. The object is to provide a heated cabinet that will display the goods, protect them from dust, and keep them heated to a practically uniform temperature. By employing electricity as the heating agent, I avoid the inconvenience, bad odor, and extra cabinet space that would be caused by the use of a fuel burner.

Referring to the accompanying drawings: Fig. 1 is a rear elevation of a cabinet embodying my invention, portions of the door being broken out to expose the heating element and one of the lights; Fig. 2 is a diagram of the electrical connections in the cabinet; Fig. 3 is a sectional plan view taken on line III—III of Fig. 1, breaking a portion of the perforated heater shield; Fig. 4 is another section on line III, viewed upwardly.

The cabinet as shown comprises the base 1, the corner posts 2, and the top 3. The bottom plate 1 is wood, and is covered by a sheet metal plate 4, having its edges upturned on three sides, forming flanges 4" (Fig. 3).

The posts 2 are grooved for holding the edges of glass walls 5, which form the front and two sides of the cabinet. A door frame 6 is mounted on hinges 7 between the rear posts 2, and is fitted with a glass pane 8, and a latch 9 which holds the door in closed position.

The top 3 is secured to the posts 2 either fixedly or removably. Mounted centrally on said top is a translucent dome 10 which covers an electric lamp 12 (indicated). A second electric lamp 14 is mounted on the lower side of the top 3, for illuminating the interior of the cabinet. The top light 12 is mainly for advertising purposes.

15 denotes a glass shelf, supported by brackets 16 (Fig. 3). This shelf forms a convenient support for the commodity being sold after the same has been placed in sacks.

An electric heating element 17, Fig. 3, is placed on the bottom plate 4, though the conducting wire, if bare, will, of course, be insulated from said plate the latter being 60 metal.

With this heater continuously energized, the temperature of the air in the cabinet would soon become too high, except in very cold weather. In order to hold the inside 65 temperature below an excessive degree, I purpose to employ a "make-and-break" thermostat, connecting same in series with the heating element and with a source of electric current. Preferably, I locate the 70 thermostat, marked 18, at the top of the cabinet; Fig. 4 showing it as secured to the top plate 3.

The connections are diagrammed on Fig. 2, in which the two wires 19 represent a lamp 75 cord connected with a commercial lighting circuit. The wires supplying the thermostat 18 and the heater 17 are connected as shown. Thus the operation of the heater will be unaffected by the condition of the 80 lamps 12, 14 as to "on" or "off."

When the temperature becomes too high, the thermostat will open the heater circuit and will hold the same open until the temperature has fallen to the point for which 85 the thermostat has been adjusted; when the circuit will be re-closed and the heating process resumed.

Preferably, the top of the cabinet is to be without openings, excepting the small 90 holes made to pass the electric cord 19 into the cabinet.

As shown on Fig. 3, a suitable shield 20 is secured to the base over the heating element, for holding the nuts from contact with 95 the heating element. This shield is perforated, as shown at 21, to permit circulation of air through the shield.

The loose nuts are placed upon the bottom plate to a depth of several inches. They 100 will in time become uniformly heated from the heating element 17. Sacks filled with the nuts are laid on the shelf 15, where they will be kept hot and ready for dispensing.

The entire metal plate 4, upon which the 105 heating element rests, will be raised in temperature by heat emitted by the heater 4, and said plate will thus constitute an extended heating surface whereby the nuts not directly above the element 4 will be 110 heated.

Having now described my invention, I

claim, and desire to secure by Letters Patent: ing said element; a door in said cabinet; and 10

In a display and heating cabinet for a shelf extending half-way across the cabinet nuts and the like, a rectangular closed structure provided with a plurality of glass walls, at a height about midway between the top and bottom thereof substantially as described.

5 a top and a bottom; a metal heating-plate covering a relatively large portion of said bottom; an electric heating element mounted with its heating surface in direct contact with said plate; a perforated shield enclos-

[Signed.] WILLIAM L. BROWN.
